UNITED STATES PATENT OFFICE.

BARNEY R. BROWN, OF HEBER SPRINGS, ARKANSAS.

DESIGN FOR A RADIATOR-CAP ORNAMENT OR SIMILAR ARTICLE.

Application filed September 17, 1925. Serial No. 14,804. Term of patent 7 years.

To all whom it may concern:

Be it known that I, BARNEY R. BROWN, a citizen of the United States, residing at Heber Springs, in the county of Cleburne and State of Arkansas, have invented a new, original, and ornamental Design for a Radiator-Cap Ornament or Similar Article, of which the following is a specification, reference being had to the accompanying drawing, forming part thereof.

Figure 1 is a view in front elevation of a radiator cap ornament or similar article embodying my design; and

I claim:—

The ornamental design for a radiator cap ornament or similar article, as shown.

BARNEY R. BROWN.
